(57) **CLAIM**

I claim the ornamental design for a light fixture, as shown
and described.

DESCRIPTION

FIG. 1 is a front view elevation of a light fixture showing my
new design, the rear view elevation being a mirror image
thereof.

FIG. 2 is a top plan view thereof; and

FIG. 3 is a bottom view thereof; and

FIG. 4 is a top perspective view thereof; and,

FIG. 5 is a bottom perspective view thereof.

The broken lines which define the bounds of the claimed
design form no part thereof.
